(57) **CLAIM**

We claim the ornamental design for a display panel with transitional graphical user interface, as shown and described.

DESCRIPTION

FIG. 1 is a front view of a first image of a display panel with transitional graphical user interface showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; and, FIG. 9 is a front view of a ninth image thereof.

The broken lines in the drawing figures are included for the purpose of illustrating environment and form no part of the claimed design.

The appearance of the image transitions sequentially between the images shown in FIGS. 1 to 9. The process or period in which one image transitions to another forms no part of the claimed design.
